UNITED STATES PATENT OFFICE

PAUL E. FENTON, OF THOMASTON, CONNECTICUT, ASSIGNOR TO SCOVILL MANUFACTURING COMPANY, OF WATERBURY, CONNECTICUT, A CORPORATION OF CONNECTICUT

RESILIENT BUTTON LOOP

Application filed April 7, 1930. Serial No. 442,318.

This invention relates to button loops such as are used on the shoulder straps or suspenders of overalls, jumpers and similar garments.

Such button loops are customarily formed of a length of wire bent to form a strap engaging member and a pair of resilient arms so shaped as to provide a relatively large aperture for the passage of the button head and a relatively small aperture to embrace the button hub and prevent disengagement of the button from the button loop, the two apertures being separated by bends forming a constricted passage between them of less width than the diameter of the button hub. The ends of the arms are so arranged and connected as to permit their separation by spring action to an extent sufficient to allow the button hub to pass from the large aperture into the small aperture.

Various means have been devised for appropriately connecting the free ends of the arms, and it is to means of this character that the present invention is primarily directed.

The object of the invention is to provide a button loop of substantially the type referred to, having a connecting member for the free ends of the arms of such a character that it will embrace these ends but will permit of their required relative movement or separation.

This connecting member not only produces a neat and attractive button loop but one in which the free ends of the arms are so joined as to be enclosed and thus no rough edges, sharp ends and corners, and other undesirable projections are present to catch in and injure the fingers and clothing of the user.

The invention contemplates a button loop having a pair of resilient arms adapted to embrace a button hub, these arms terminating in bends so formed as to receive lugs carried by a connecting member, preferably of sheet metal, embracing the terminals of the arms and enclosing them, the relative dimensions of the bends and lugs being such as to permit limited separation of the arms for

the purpose mentioned, as I will proceed now more particularly to explain and finally claim.

In the accompanying drawings illustrating the invention, in the several figures of which like parts are similarly designated, Figures 1 and 2 are front and back views, respectively, of a button loop made in accordance with my invention. Fig. 3 is an enlarged view similar to Fig. 1, but showing the connecting member in section and illustrating in broken lines the separated position of the arms. Fig. 4 is a section taken on line 4-4 of Fig. 3. Fig. 5 is a section taken on line 5-5 of Fig. 3. Fig. 6 is a detail perspective view, on an enlarged scale, of the connecting member, a portion thereof being broken away. Figs. 7, 8 and 9, are, respectively front, back and edge views, on the scale of Figs. 1 and 2, of a button loop having a connecting member of modified form.

The button loop is made of a length of resilient or spring wire so bent as to form a strap engaging portion 1 from which extend resilient arms 2 curved to provide a relatively large aperture 3 to permit passage therethrough of a button head, and a relatively small aperture 4 adapted to engage the button hub, these apertures being separated by a constricted passage formed by the bends or elbows 5. The arms terminate in bends or eyes 6 preferably of elongated form, as shown, into which extend lugs 7 stamped out of one leg 8 of the preferably U shaped connecting member 9.

These lugs 7 are of less width than the openings of the bends or eyes 6 and hence permit the legs 2 to separate to an extent limited by them, as illustrated in broken lines in Fig. 3. Moreover, as shown in Fig. 5, the lugs 7 preferably extend from the leg 8 of the connecting member completely through the eyes 6 and abut against the opposite leg 10, thus not only limiting the separation or spreading apart of the arms 2 as the button hub moves from the aperture 3 into the aperture 4 past the restriction formed by the elbows or bends 5, but holding the connecting member in position upon the ends or terminals of the arms 2.

In the form of the invention illustrated in Figs. 1 to 6, the connecting member is formed with a tongue 11, preferably on the leg 8, which is bent over between the arms 2 adjacent to the bends or eyes 6 and forms a bearing member for the hub of the button. Preferably the edge of the leg 10 is cut away thus forming a recess as indicated at 12, to receive the end of the tongue 11 substantially flush with the outer face of the leg 10.

By bending the connecting member 9 to the shape illustrated, around the bends or eyes 6, it will be apparent that the terminals of the arms 2 are completely enclosed or housed, and hence no rough edges are presented, nor can anything be caught or pinched between the terminals.

Furthermore, the connecting member closes the bottom of the button loop and provides the bearing for the button hub.

As will be seen by reference particularly to Figs. 1 and 4, when the arms 2 are in their normal position, the tongue 11 forming the bearing member engages the bends or eyes 6 and hence prevents any tendency for the legs 8 and 10 of the connecting member 9 to spread apart. This is not essential, however, for the reason that the member 9 will be made of material of sufficient stiffness to retain its shape when once closed in upon the eyes 6, it being understood, of course, that sufficient clearance is provided to permit free spreading or separation of the arms 2 in the manner described. The principal function of the tongue 11 is as a bearing member for the button hub, and it has the added attribute of enhancing the finish and attractive appearance of the connecting member 9 in its association with the button loop.

The tongue 11 may be omitted, if desired, as illustrated in the modified form of the invention shown in Figs. 7 to 9.

Various changes other than those referred to are contemplated as within the spirit of the invention and the scope of the following claims.

What I claim is:—

1. A button loop, having a pair of resilient arms terminating in eyes, and a sheet metal connecting member bent to U shape about said eyes and embracing same and having its adjacent edges facing said loop, said member provided with lugs extending into said eyes, one of said edges provided with a bearing member offstanding from it and bent between said arms adjacent to said eyes to form a bearing for a button shank.

2. A button loop, having a pair of resilient arms terminating in elongated eyes, and a connecting member of sheet metal bent to U shape applied to and forming legs embracing said eyes, one leg of said member provided with lugs extending through said eyes and engaging the oppo-

site leg, said lugs being of less width than the width of said eyes, whereby limited separation of said arms is permitted as determined by the relative widths of said lugs and eyes.

3. A button loop, having a pair of resilient arms terminating in eyes, and a connecting member of sheet metal bent to U shape and embracing said eyes and having its adjacent edges facing said loop, said connecting member provided with lugs integral with one leg of said U and extending through said eyes, one edge of said member provided with a tongue bent between said arms and the other edge provided with a recess to receive the end of said tongue, said tongue forming a bearing for a button shank, and said connecting member serving to connect said arms and limit their separation.

4. A button loop comprising a pair of spring arms cooperatively bent to form associated loops in axial alignment and having an intermediate contracted portion, the extremities of the arms having looped enlargements normally abutting and providing elongated eyes, and a clip coupling securing the enlargements therein with a limited freedom of movement by means of lugs provided by the clip for relative sliding movement within the eyes.

In testimony whereof I have hereunto set my hand this 4th day of April, A. D. 1930.

PAUL E. FENTON.
